UNITED STATES PATENT OFFICE.

GEORGE SAGUE, OF OAKES, NEW YORK.

PRINTING PRESS.

Application filed September 2, 1922. Serial No. 585,868.

To all whom it may concern:

Be it known that I, GEORGE SAGUE, a citizen of the United States, and a resident of Oakes (Highland Post-Office), in the 5 county of Ulster and State of New York, have invented certain new and useful Improvements in or Relating to Printing Presses, of which the following is a specification.

10 The invention comprises a new method of and novel apparatus for cleaning all of the inked surfaces of a printing press, including the form-cylinder and ink-distributing rollers, while the same are on the press 15 and driven from the mechanism thereof.

Many attempts have been made to efficiently clean composition ink-distributing rollers and the other inked surfaces of a printing press, and these attempts have met 20 with difficulties, especially when the efforts have been to clean the ink-distributing rollers while on the press.

One of the difficulties encountered in the attempt to clean the composition ink-distributing rollers while on the press arose 25 from the fact that the solvent was distributed along the whole length of one or more of the rollers and the scraper was applied along the whole length of the roller. 30 This method of procedure resulted in the composition rollers becoming so lubricated with the solvent that the gear-driven steel rollers merely slipped on the composition rollers without driving the same. One attempt 35 to remedy this difficulty was to change the mechanism of the press so that all of the composition rollers instead of being frictionally driven by the metal rollers, were equipped with gear wheels so that 40 they could be gear-driven.

In accordance with my invention I do not modify the construction or mechanism of the press, but apply a series of spiral scrapers thereto, there being one scraper 45 for each composition ink-distributing roller, and operate these scrapers simultaneously toward and from the rollers from a single source of manually applied power, the scrapers by reason of their spiral form, not 50 at once engaging the whole length of the composition rollers, but having a gradual or progressive application thereto along the length thereof. In accordance with my invention I do not apply the solvent along 55 the whole length of the composition roller but apply the same by a step by step pro-

cedure, along the length of the roller, in harmony with the gradual application of the spiral scraper blade to the roller along its length, so that the scraper blade acts 60 progressively and along that portion of the roller which is receiving the solvent, the surface of the roller both in advance and in rear of the portion thereof receiving the solvent and in engagement with the scraper 65 being left in condition to frictionally coact with the metal roller from which it receives motion.

The mechanical features of my invention may be built into the printing press or applied to the same as an attachment after 70 the press has been built.

In the drawings I illustrate my invention applied to the press shown as an attachment, the press having already been constructed and in use, and my invention having been applied to the press for efficiently cleaning the form cylinder and ink-distributing rollers while on and driven by 75 the press. In applying my attachment to the press shown in the drawings no change whatever was made in the press nor in the arrangement of the ink-distributing rollers. My invention is intended for presses having different systems of ink-distributing rollers 80 from that shown in the drawings, and therefore I do not limit the invention to the particular press or arrangement of distributing rollers shown in the drawings. 85

The invention will be fully understood 90 from the detailed description hereinafter presented, reference being had to the accompanying drawings, in which:

Fig. 1 is a longitudinal vertical section through a printing press equipped with the 95 inked-surface cleaning-mechanism embodying my invention, the press itself being of ordinary type, the section cutting off the front side frame of the press and the form cylinder and rollers being shown in end 100 elevation;

Fig. 2 is a like view taken from the other side of the press, the side frame of the press at that side being cut off to disclose the features of my invention, and the ends of the rollers and the end of the form cylinder shown in Fig. 2 being the opposite of the ends thereof shown in Fig. 1;

Fig. 3 is a detached view of one of the scrapers;

Fig. 4 is a side elevation, partly broken away and partly in section, of the same, to-

gether with adjacent portions of the frames in which the ends of the scrapers are pivotally mounted, the section being on the dotted line 4—4 of Fig. 1;

5 Fig. 5 is a vertical transverse section through the same taken on the dotted line 5—5 of Fig. 4;

10 Fig. 6 is a corresponding section through the same taken on the dotted line 6—6 of Fig. 4, and

15 Fig. 7 is a like section through the same taken on the dotted line 7—7 of Fig. 4.

In the drawings, 10 designates a portion of the frame of a printing press, 11 the ink 20 fountain, and 12 the form cylinder, while 13, 14, 15, 16, 17 and 18 respectively designate customary metal ink distributing rollers, which are positively gear-driven as usual, by the mechanism of the press, all 25 features indicated being of well-known character and arrangement.

The composition ink distributing rollers at the upper side of the press are numbered, respectively, 19, 20, 21, 22, 23, 24 and 25, 30 and the composition ink distributing rollers at the lower side of the press are numbered, respectively, 26, 27, 28, 29, 30 and 31, and all these composition ink distributing rollers are of known type and arrangement and 35 in themselves constitute no part of my invention. The composition ink distributing rollers just referred to are further indicated in Fig. 1 by the presence thereon of arrows, which also denote the direction of rotation 40 of said rollers, and all of these composition rollers are driven by their frictional engagement with the metal ink-distributing rollers, as usual.

45 My invention has reference to means for cleaning the form cylinder 12 and all of the ink distributing rollers simultaneously while said cylinder and rollers are being driven by the press.

50 In carrying out my invention I mount adjacent to the inner faces of the opposite sides of the press two correspondingly shaped plates 32 of the irregular outline, more clearly illustrated in Fig. 2, to receive the rockable scrapers hereinafter described, although I may say that the outlines of these plates are unimportant so long as said plates at their edges escape the shafts of the ink distributing rollers and permit the proper positioning of the 55 features of my invention. The plates 32 for different presses will necessarily vary in outline because different presses have different numbers of ink distributing rollers and different dispositions thereof. My invention is applicable for efficiently cleaning the ink distributing rollers and other inked surfaces of the press, regardless of the number of rollers used and regardless of their particular arrangement with relation 60 to one another. The plates 32 therefore

65 shown in the drawings have an outline adapting them to the particular ink distributing rollers shown in the drawings. The plates 32 may be sustained on cross- 70 rods 33 extending between the sides of the press and at one end on a cross-beam 34 extending between said sides. The details of my invention shown in the drawings were designed for and applied to a printing press 75 of the construction shown, but these details will necessarily be modified in form and relation to suit other presses to which the invention is equally applicable.

I mount in bearings pivotally held in the plates or frames 32, a series of transverse 80 scrapers 35, there being one scraper adjacent to and for each of the composition rollers of the press, and the details of one of these scrapers being shown in Figs. 3 to 7 inclusive. The scrapers 35 are rockable so 85 that they may be moved into operative relation to the composition rollers whenever it is desired to clean the same and the form cylinder and thereafter be retired therefrom, and the means for turning said scrapers into 90 operative position and retiring the same therefrom consist of a series of cranks or levers connected with said scrapers at one side of the press and links connecting said 95 levers so that all of the scrapers may be operated in unison from one source of manually applied power, as, in the present instance, a rod 36 connected to the lever 37 of one scraper and having a threaded outer 100 end on which is mounted a hand-wheel 38 whose hub is internally threaded and which is confined in a fork 39, whereby on the rotation of said wheel in one direction the rod 36 will be moved inwardly and turn the lever 37 to apply its scraper to the adjacent 105 roller 25 and through the link-and-lever connections shown cause all the other scrapers to be applied to their respective rollers, and on the rotation of said wheel in the reverse 110 direction said rod will be drawn outwardly and turn the lever 37 to carry its scraper from the roller 25 and to effect through the connected series of links and levers, the retirement of all the other scrapers from their 115 respective rollers. In Figs. 1 and 2 all of the scrapers 35 are shown as retired from their respective composition rollers or in an initial position ready to be moved into engagement with said rollers.

120 The scrapers are all alike in respect to their construction and mode of operation and a description of one of said scrapers will answer for all of them, and after one of the scrapers has been described I will point out the lever and link connections whereby all the scrapers have simultaneous motion imparted to them from a single manually operated element of the mechanism.

125 Referring to Figs. 3 to 7 inclusive, 130

designates the scraper blade, 41 a backing plate to which the blade 40 is adjustably secured and which is U-ed at its lower portion, as at 42, to form a trough, and 43 main supporting end frames substantially conforming to and receiving the end portions of the plate 41, which is secured to said frames 43 by means of rivets or screws 44. The blade 40 is secured to the plate 41 by means of screws 45 which pass through vertically elongated slots 46 in the blade (Fig. 4), whereby the blade may be adjusted vertically to properly set the outer edge of the same with relation to the composition roller it is designed to clean. The blade 40 is slightly longer than the roller it is to clean and is rounded off at the ends of its operating edge, as at 47, to avoid injury to the roller.

20 The blade 40 has a spiral set, as I represent in Figs. 5, 6 and 7, which show several sections of the blade and indicate the relative positions thereof, Fig. 5 illustrating the set of one end of the blade, Fig. 7 that of the other end of the blade and Fig. 6 that of the middle of the blade. The spiral formation of the blade 40 is gradual and uniform from one end to the other thereof and is not of great extent, as may be seen on reference to Fig. 3 and also by a comparison of the end portions of the blade shown in Figs. 5 and 7. The spiral formation of the blade 40 constitutes an important feature of my invention.

30 35 The end frames 43 are castings and they cradle the end portions of the plate 40 and its trough 42, and said frames 40 are formed at their outer ends with corresponding extensions 48 which have flattened sides and respectively enter bearing sleeves 49, 50 rotatably mounted in apertures in the plates 32. The bores 51 of the sleeves 49, 50 have flattened sides to snugly receive the sides of the extensions 48 but loosely enough to permit said extensions to have a transverse sliding movement in said bores, which are elongated beyond the dimensions of said extensions, as shown in Figs. 4 and 5. I preferably line the flat sides of the bores 51 with smooth flat face plates 52 against which the flat sides of the extensions 48 have sliding engagement. Within the bores 51 I arrange cushioning springs 53 below and preferably partly entering the extensions 48, as shown in Fig. 4, to cushion the engagement of the edge of the blade 40 with the roller it is to clean and to render the blade self-adjustable to the roller.

50 60 The sleeves 49, 50 are positioned in the apertures in the plates 32 by outer flanges 54 and inner collars 55, according to well-known methods.

The scraper 35 shown in detail in Figs. 4 to 7 inclusive, is the scraper for cleaning the roller 19, Fig. 4 being a section on the

line 4—4 of Fig. 1, and the position of this scraper with relation to the roller 19 is clearly illustrated in Fig. 1. The sleeve 50 at one end of the said scraper 35 is, as shown in Fig. 4 as well as in Fig. 1, formed with a crank-arm 56, whose connection to the source of manually applied power will be presently referred to.

All of the scrapers 35 are mounted in the plates 32 in the manner illustrated in Fig. 4, and the tubular bearing sleeves 50 for all of the scrapers have crank-arms formed thereon adapted to receive link connections whereby all of the scrapers will be given substantially corresponding motion from the operating rod 36. The rod 26 is pivotally connected with the bell crank lever 37, as shown in Fig. 2, and by starting with the lever 37 one may follow the lever and link connections throughout the system thereof. The bell-crank lever 37 is connected with the scraper 35 for the roller 25, and the arm 57 of said bell-crank lever 37 is connected by a link 58 with a lever 59 on the bearing of the scraper 35 for the composition roller 31, as shown in Figs. 1 and 2, whereby said scraper for the roller 31 is given simultaneous movement with the scraper 35 for the roller 25. The lever 59 is of bell-crank type and the arm 60 thereof is connected by a link 61 with a lever 62 on the tubular bearing of the scraper 35 for the composition roller 30, and said lever 62 is connected by a link 63 with the lever 64 of the scraper 35 for the composition roller 29, and also by a link 65 with the lever 66 of the scraper 35 for the composition roller 27. The lever 64 is of bell crank type, and one arm thereof is connected by a link 67 with the lever 68 of the scraper 35 for the composition roller 28.

The arm 57 of the initial operating lever 37 is also connected by a link 69 with the lever 70 of the scraper 35 for the composition roller 24, and said lever 70 is connected by a link 71 with the bell crank lever 72 of the scraper 35 for the composition roller 22. One arm of the lever 72 is connected by a link 73 with the lever 74 of the scraper 35 for the composition roller 23.

The lever 59 of the scraper for the roller 31 is connected by a link 75 with the bell crank lever 76 of the scraper for the composition roller 21, and one arm of the lever 76 is connected by a link 77 with the lever 78 of the scraper for the composition roller 20. The lever 78 is connected by a link 79 with the lever 56 of the scraper for the composition roller 19, and said lever 78 is also connected by a link 80 with the lever 81 of the scraper 35 for the composition roller 26.

It will thus be seen that the manually operated rod 36 communicates motion to the bell crank lever 37, and that from this lever, through the series of links identified and the levers of the scrapers, motion

is simultaneously imparted to all of the scrapers of the series for all of the composition rollers, all of said scrapers receiving the same movement as the scraper 35 connected with the prime lever 37. The system of links and levers shown in Fig. 2 permits me to rotate or rock all of the scrapers 35 with relation to their respective composition rollers, all of the scrapers 10 operating in unison and having like movements. It is the purpose of my invention that all of the inked surfaces of the press, including the form cylinder and ink distributing rollers, shall be simultaneously cleaned while on and driven by the press, and hence I provide that all of the scrapers 35 shall operate together and from a single source of manually applied power. I deem it essential that the scrapers 35 20 be manually operated, since the thorough cleaning of the press requires only a few minutes and because I deem it better that the operator may observe the progress made in the cleaning of the press and apply 25 the solvent and scrapers in such manner as to assure the rapid and efficient cleaning of all the ink, paper-dust and the like, from the inked surfaces of the press.

In the operation of cleaning the press I 30 first throw out the impression cylinder from the form cylinder and cut out the mechanism of the ink fountain so that no ink will be fed during the cleaning operation. This leaves the form cylinder and all of 35 the ink-distributing rollers in their normal position and relation, and during the cleaning process, the mechanism of the press being in motion, the metal ink-distributing rollers will be gear-driven, as usual, and 40 the composition ink-distributing rollers will be driven by their frictional engagement with the metal ink-distributing rollers.

One operator will, by means of the hand 45 wheel 38, rod 36, and the series of link and lever connections hereinbefore referred to, rotate or rock the scrapers 35 in a direction toward their respective composition rollers, and another operator will apply a solvent, such as kerosene, or any of 50 the other known solvents, gradually along the surface of one of the composition rollers. It is almost unimportant to which of the composition rollers the solvent may 55 be manually applied. The solvent may be applied, for illustration, to the composition roller 22. In carrying out my method the manner of applying the solvent to the roller 22 and the movement of the scrapers 60 to the rollers are matters of importance. The scrapers 35 are spiral, in respect to the blades 40 and troughs 42, and the scraper blades 40 will at one end reach 65 and act against the composition rollers in advance of the other portions of said blades

reaching said rollers, so that there will be a gradual application of the scraper blades along their length to the rollers, this being a feature of importance.

The solvent is applied to the roller 22, 70 or any other roller of the series, at the end thereof at which the scraper blade 40 first engages the roller, there being a gradual traveling application of the solvent along the roller 22 in a direction from said end thereof in about the same proportion as the scraper blade 40 is rocked toward and engages successive portions of the surface of said roller, the applications of the solvent being on successive sections of the 75 roller in harmony with the approach of successive sections of the spiral blade 40 to and against the roller. The scraper blade 40 is rocked toward the roller 22 in timing with the application of the solvent to and along 80 successive portions of the roller, so that when the solvent is being applied to the far end of the roller 22 that portion of the scraper blade 40 which was initially farthest from the roller 22 will engage said roller. It 85 will thus be seen that the solvent is not applied along the whole surface of the roller 22 or other roller at one time and that the scraper blade 40 does not engage 90 the whole length of the roller at once, but has a gradual movement toward and against the same. The operating rod 36 will be continued on its inward movement until the scraper blades 40 of all of the scrapers 95 have along their full length moved, with a continuous traveling engagement, against the rollers and have passed beyond their engagement with the rollers, and at this time I reversely repeat the cleaning operation by moving the rod 36 outwardly to 100 reverse the direction of motion of the scraper blades against their rollers and apply the solvent as before but commencing 105 at the opposite end of the roller 22 from that to which the solvent was applied in 110 the first stage of the cleaning operation, and during this reverse motion of the scrapers the solvent will be gradually applied along the roller 22 in timing with 115 the engagement with the roller of successive portions of the scraper blades, the outward movement of the rod 36 being continued until the scrapers have retired from the rollers and are back to their initial position shown in Fig. 1. If for any reason 120 the rollers should not by this time have been entirely cleaned, the two stages of the cleaning operation just described may be at once repeated. I have found that in 125 the space of five minutes the press having the rollers shown in the drawings and equipped with my mechanism, may be efficiently cleaned. The ink on the rollers is softened by the solvent applied thereto, and the foreign matter removed by the scrapers 130

passes into the troughs 42 which may be cleaned out as often as may be necessary. It is of importance that my method of cleaning the rollers be followed, that is the gradual application of the solvent along the length of a feed roller, as 22, and the gradual application of the scraper blade to the roller along that portion thereof which is receiving the solvent. The solvent applied to one of the rollers, as 22, is quickly distributed to all of the rollers, as well as to the surface of the form cylinder, and hence solvent applied to any one section of the roller 22 will almost immediately appear on the corresponding section of all of the other rollers and also of the form cylinder.

In accordance with my method of procedure I do not apply the solvent along the whole length of the roller, as 22, selected to initially receive the solvent, but, as aforesaid, apply the solvent by degrees and gradually along the length of the roller 22 while causing the corresponding approach of the scraper blade to the roller, with the result that at all times there are abundant surfaces of the rollers lacking the solvent to assure the continued rotation of the composition rollers by their frictional engagement with the metal rollers. The solvent is along progressive sections of the composition rollers removed by the scrapers, the solvent being applied to the feed roller at successive sections thereof and transferred to the other rollers at like sections thereof from one end to the other of said rollers and then in like manner back to the first end of the rollers, as often as may be necessary, and the surfaces of the rollers both in advance and in rear of the portions thereof in engagement with the scrapers being left in condition to frictionally coat with the metal rollers, whereby the composition rollers remain in rotation during the cleaning operation.

During the cleaning of the rollers and form cylinder the ink and solvent on the form cylinder transfers to the composition rollers 23, 24, 25, 29, 30 and 31, and the ink on the steel distributing rollers likewise transfers to the composition rollers with which they are in frictional engagement, and the solvent and ink on the composition rollers are removed from each roller by the scraper provided therefor. The composition rollers act to draw or feed off the solvent and ink from the form cylinder and steel distributing rollers, and hence when the ink and solvent are removed from the composition rollers, the entire inked surfaces of the press become clean. I apply only a small quantity of solvent at a time to the roller 22, or other selected composition roller of the series, since the solvent becomes quickly distrib-

uted from the successive sections of the supply or feed roller to corresponding successive sections of all of the other rollers and to the form cylinder of the press.

My invention provides a new method for the cleaning of the inked surfaces of the press and also novel means for carrying the invention into effect, the new method consisting in the application of the solvent to successive sections of a rotating composition roller along the length thereof and the application of successive sections of the scraper blade to the roller at those successive portions thereof receiving the solvent, leaving the other portions of the roller free for frictional engagement with the adjacent roller by which it is driven or rotated.

I do not limit my invention to all of the special details of form and construction hereinbefore described, since I am aware that the same may be modified within the spirit of my invention and the scope of the appended claims. I desire to receive adequate protection for my invention.

What I claim as my invention and desire to secure by Letters Patent, is:

1. Means for cleaning the surface of a rotating composition printing press roller, comprising a pivotally mounted scraper having a spiral scraper blade extending the whole length of the roller and being of such pitch that its entire edge forms only a fraction of a convolution, means for rolling successive sections of said blade directly against and away from said roller and means whereby an ink-solvent is applied to corresponding successive sections of the roller.

2. The method hereinbefore described of cleaning the surface of a composition ink-distributing roller of a printing press, which consists in rotating the roller, applying an ink-solvent to successive sections of the roller from one end to the other thereof, rolling successive sections of a spiral scraper blade against the successive portions of the roller receiving the solvent until the blade passes the line of contact with the roller, then reversing the movement of the scraper blade against the roller and applying solvent to successive portions of the roller commencing with the end thereof first engaged by the scraper blade on its reverse movement back to its initial position.

3. The method hereinbefore described of cleaning the surfaces of a series of ink-distributing rollers of a printing press, some of said rollers being the usual metal rollers and the others being composition rollers in surface contact with the metal rollers, which consists in driving all said rollers by power applied to the metal rollers, applying an ink-solvent to successive sections of one of the rollers and permit-

ting the same to transfer to like sections of the other rollers, and simultaneously rolling successive sections of spiral scraper blades against the successive portions of the 5 composition rollers receiving the solvent.

4. The method hereinbefore described of cleaning the surfaces of a series of ink-distributing rollers of a printing press, some 10 of said rollers being the usual metal rollers and the others being composition rollers in surface contact with the metal rollers, which consists in driving all said rollers by power applied to the metal rollers, applying an 15 ink-solvent to successive sections of one of the rollers and permitting the same to transfer to like sections of the other rollers, simultaneously rolling successive sections of spiral scraper blades against the successive portions of the composition rollers receiving 20 the solvent until the blades pass their line of contact with the rollers, then reversing the movement of the scraper blades against the rollers and applying solvent as before commencing at the ends of the rollers 25 first engaged by the scraper blades on their reverse movement back to their initial position.

5. Means for cleaning the surface of a rotating composition printing press roller, 30 comprising a pivotally mounted scraper having a spiral scraper blade and a refuse receiving trough at the lower edge thereof, and means for rolling successive sections of said blade against and from said roller 35 while an ink-solvent is applied to corresponding sections of the roller, said blade extending the whole length of the roller and being of such pitch that its entire edge forms only a fraction of a convolution.

40 6. Means for cleaning the surface of a rotating composition printing press roller, comprising a pivotally mounted scraper having a spiral scraper blade and means cushioning the same, and means for rolling successive sections of the blade against and from said roller while an ink-solvent is applied to corresponding sections of the roller, said cushioning means allowing the scraper-blade to yield to the roller when in engagement 45 therewith, and said blade extending the whole length of the roller and being of such pitch that its entire edge forms only a fraction of a convolution.

7. Means for cleaning the surface of a 55 rotating composition printing press roller, comprising a pivotally mounted scraper having a spiral scraper blade, means cushioning the same and a refuse-receiving trough at the lower edge of the blade, and 60 means for rolling successive sections of the blade against and from said roller while an ink-solvent is applied to corresponding sections of the roller, said cushioning means allowing the scraper blade 65 to yield to the roller when in engagement

therewith, and said blade extending the whole length of the roller and being of such pitch that its entire edge forms only a fraction of a convolution.

8. Means for cleaning the surface of a 70 rotating composition printing roller, comprising a scraper having a spiral scraper-blade and end extensions having flattened sides, side plates at the ends of the scraper, rotary bearing sleeves mounted in said side 75 plates and having bores formed with flattened sides and receiving said extensions, and means connected with one of said sleeves for rolling successive sections of said blade against said roller while an ink-solvent is 80 applied to corresponding sections of the roller.

9. Means for cleaning the surface of a rotating composition printing press roller 85 comprising a scraper having a spiral scraper blade, a refuse receiving trough along the lower edge thereof and end extensions having flattened sides, side plates at the ends of the scraper, rotary bearing sleeves mounted in said side plates and having bores 90 formed with flattened sides and receiving said extensions, and means connected with one of said sleeves for rolling successive sections of said blade against said roller while an ink solvent is applied to successive sections of the roller.

10. Means for cleaning the surface of a rotating composition printing press roller, comprising a scraper having a spiral scraper blade, cushioning means therefor and end extensions having flattened sides, side plates at the ends of the scraper, rotary bearing sleeves mounted in said side plates and having bores formed with flattened sides and receiving said extensions, and means connected 100 with one of said sleeves for rolling successive sections of said blade against said roller while an ink solvent is applied to corresponding sections of the roller, said cushioning means allowing the scraper blade to yield to the roller when in engagement therewith.

11. Means for cleaning the surface of a rotating composition printing press roller 115 comprising a scraper having a spiral scraper blade and end extension having flattened sides, side plates at the ends of the scraper, rotary bearing sleeves mounted in said side plates and having bores formed with flattened sides and receiving said extensions, springs mounted in said bores below said extensions and partly entering the same for cushioning the scraper, and means connected with one of said sleeves for rolling successive sections of said blade against said roller, said springs allowing the scraper blade to yield to the roller when in engagement therewith.

12. Means for cleaning the surfaces of a 120 series of rotating ink-distributing rollers of 125

- a printing press, some of said rollers being the usual metal rollers and the others being composition rollers in surface contact with the metal rollers, comprising pivotally mounted scrapers having spiral scraper blades, one scraper being provided for each composition roller, and means for simultaneously rolling successive sections of said blades against said composition rollers, 10 while an ink solvent is applied to corresponding sections of one of the rollers and permitted to transfer to like sections of the other rollers.
13. Means for cleaning the surfaces of a series of rotating ink-distributing rollers of a printing press, some of said rollers being the usual metal rollers and the others being composition rollers in surface contact with the metal rollers, comprising pivotally mounted scrapers having spiral scraper blades, one scraper being provided for each composition roller, and means for simultaneously rolling successive sections of said blades against said composition rollers, while 20 an ink solvent is applied to corresponding sections of one of the rollers and permitted to transfer to like sections of the other rollers, said scrapers each having a refuse receiving trough at the lower edge thereof.
14. Means for cleaning the surfaces of a series of rotating ink-distributing rollers of a printing press, some of said rollers being of usual metal rollers and the others being composition rollers in surface contact with the metal rollers, comprising pivotally mounted scrapers having spiral scraper blades, one scraper being provided for each composition roller, and means for simultaneously rolling successive sections of said blades against said composition rollers, while 30 an ink solvent is applied to corresponding sections of one of the rollers and permitted to transfer to like sections of the other rollers, said scrapers each having a refuse receiving trough at the lower edge thereof.
15. Means for cleaning the surfaces of a series of ink distributing rollers of a printing press, some of said rollers being the usual metal rollers and the others being composition rollers in surface contact with the metal rollers and driven by the mechanism of the press, comprising scrapers, one for each composition roller, having a spiral scraper blade and end extensions having flattened sides, side plates at the ends of the scrapers, rotary bearing sleeves mounted in said side plates and having bores formed with flattened sides and receiving said extensions, lever arms connected with the sleeves at one end of said scrapers, link connections connecting all of said lever arms for simultaneous operation, and manually operative means connected with said levers and links for imparting simultaneous motion thereto from a single source of power, said manually operative means being adapted to operate said links and levers for simultaneously rolling successive sections of said blades against their rollers in the presence of an ink solvent on the rollers.
16. Means for cleaning the surfaces of a series of ink distributing rollers of a printing press, some of said rollers being the usual metal rollers and the others being composition rollers in surface contact with the metal rollers and driven by the mechanism of the press, comprising scrapers, one for each composition roller, having a spiral scraper-blade and end extensions having flattened sides, side plates at the ends of the scrapers, rotary bearing sleeves mounted in said side plates and having bores formed with flattened sides and receiving said extensions, lever arms connected with the sleeves at one end of said scrapers, link connections connecting all of said lever arms for simultaneous operation, and manually operative means connected with said levers and links for imparting simultaneous motion thereto from a single source of power, said manually operative means being adapted to operate said links and levers for simultaneously rolling successive sections of said blades against their rollers in the presence of an ink solvent on the rollers.
17. Means for cleaning the surfaces of a series of ink distributing rollers of a printing press, some of said rollers being the usual metal rollers and the others being composition rollers in surface contact with the metal rollers and driven by the mechanism of the press, comprising scrapers, one for each composition roller, having a spiral scraper blade and end extensions having flattened sides, side plates at the ends of the scrapers, rotary bearing sleeves mounted in said side plates and having bores formed with flattened sides and receiving said extensions, lever arms connected with the sleeves at one end of said scrapers, link connections connecting all of said lever arms for simultaneous operation, and manually operative means connected with said levers and links for imparting simultaneous motion thereto from a single source of power, said manually operative means being adapted to operate said links and levers for simultaneously rolling successive sections of said blades against their rollers in the presence of an ink solvent on the rollers, said scrapers each having a refuse receiving trough at the lower edge thereof.
18. Means for cleaning the surfaces of a series of ink distributing rollers of a printing press, some of said rollers being the usual metal rollers and the others being composition rollers in surface contact with the metal rollers and driven by the mechanism of the press, comprising scrapers, one for each composition roller, having a spiral scraper blade and end extensions having flattened sides, side plates at the ends of the scrapers, rotary bearing sleeves mounted in said side plates and having bores formed with flattened sides and receiving said extensions, lever arms connected with the sleeves at one end of said scrapers, link connections connecting all of said lever arms for simultaneous operation, and manually operative means connected with said levers and links for imparting simultaneous motion thereto from a single source of power, said manually operative means being adapted to operate said links and levers for simultaneously rolling successive sections of said blades against their rollers in the presence of an ink solvent on the rollers.

ing press, some of said rollers being the usual metal rollers and the others being composition rollers in surface contact with the metal rollers and driven by the mechanism 5 of the press, comprising scrapers, one for each composition roller, having a spiral scraper blade and end extensions having flattened sides, side plates at the ends of the scrapers, rotary bearing sleeves mounted in 10 said side plates and having bores formed with flattened sides and receiving said extensions, lever arms connected with the sleeves at one end of said scrapers, link connections connecting all of said lever arms for 15 simultaneous operation, and manually operative means connected with said levers and

links for imparting simultaneous motion thereto from a single source of power, said manually operative means being adapted to operate said links and levers for simultaneously rolling successive sections of said blades against their rollers in the presence of an ink solvent on the rollers, said sleeves having springs mounted in their bores below said extensions for cushioning the scrapers, 25 said springs allowing the scraper blades to independently yield to the rollers while in engagement therewith.

Signed at New York city, in the county of New York and State of New York, this 30 1st day of September A. D. 1922.

GEORGE SAGUE.
